UNITED STATES PATENT OFFICE.

SETH WILLIAM BABBITT, OF MERIDEN, CONNECTICUT.

DESIGN FOR A METAL VESSEL.

SPECIFICATION forming part of Design No. 23,241, dated May 1, 1894.

Application filed April 2, 1894. Serial No. 506,113. Term of patent 3½ years.

To all whom it may concern:

Be it known that I, SETH WILLIAM BABBITT, of Meriden, in the county of New Haven and State of Connecticut, have invented a new 5 Design for a Metal Vessel; and I do hereby declare the following, when taken in connection with the accompanying drawings and the letters of reference marked thereon, to be a full, clear, and exact description of the same, 10 and which said drawings constitute part of this specification, and represent, in—

Figure 1, a side view of a bowl illustrating my design; Fig. 2, a sectional view thereof.

This invention relates to a design for a 15 metal vessel, and the design consists in the configuration and ornamentation as herein described and shown in the accompanying illustrations.

The vessel, which is here represented in the 20 form of a bowl, bends abruptly outward from the base, and then curves upward, inward, and slightly outward to the top. Upon the lower or body portion A, of the bowl, is a series of scrolls B, extending diagonally downward, and terminating at the angle formed 25 by the abrupt outward bend C in the bowl, the scrolls branching gradually outward at their lower ends as at D, the reversely curved

scroll overlapping the preceding scroll, as at a, leaving a slightly curved plain surface E 30 between each scroll, these overlapping scrolls forming a continuous line of ornamentation around the lower portion of the body of the dish. The gradually narrowing scrolls are surmounted by an overlaying reversely curved 35 scroll F. Above the scrolls is a circumferential series of waved ribs G, surrounding the bowl, the waves being broken by a scroll J over each of the scrolls F. The upper portion or border H, of the bowl is formed by an 40 elaborate open tracery I, of scrolls and foliated work in the roccoco style of ornamentation, which surrounds, and gives a broken configuration to the top of the bowl, all as shown in the accompanying illustration. 45

I claim—

The design for a metal vessel as herein shown and described.

In testimony whereof I have signed this specification in the presence of two subscribing witnesses.

SETH WILLIAM BABBITT.
